LOCOMOTIVE STRUCTURE

Karl S. Howard, St. Louis, Mo., assignor to General Steel Castings Corporation, Granite City, Ill., a corporation of Delaware

Application June 26, 1931, Serial No. 547,137

18 Claims. (Cl. 105—44)

The invention relates to railway rolling stock and more particularly to the saddle, main steam cylinders, supply valve chambers, steam passageways for the latter, boiler support, and other 5 associated structure.

In the usual cylinder saddle structure, the exhaust steam passageways from the valve chambers to the exhaust nozzle form a substantially continuous member between the valve 10 chambers. This member is rigid and is tied to the saddle and main frame members by virtue of its integral structure or of its securing elements.

The exhaust passageways are subjected to alternate heating and cooling by the intermittent 15 passage of the steam from the cylinders to the exhaust nozzle, depending on the operation of the locomotive, while the saddle and frame members are substantially of uniform temperature, 20 approximately atmospheric temperature. This condition causes internal strains in the various parts of the casting, which strains have been found to be of considerable magnitude.

The main object of the invention is to provide 25 a structure in which such strains are relieved or eliminated.

In a co-pending application Serial No. 547,136, filed June 26, 1931, having the same general object, there is disclosed a saddle structure in 30 which the exhaust steam passageways extend through openings in the side walls of the saddle and suitable plates are provided at the bottom of the smokebox and surrounding the inner ends 35 of the exhaust steam passageways to exclude air from the smokebox, the exhaust steam passageways being exposed to external air substantially throughout their length. The present invention is directed to a type of saddle structure in which the exhaust steam passageways are united with 40 the walls of the saddle and the saddle forms an air excluding chamber for the inner portions of the passageways.

The general object indicated above may be attained by separating the inner ends of the exhaust steam passageways from each other or by otherwise arranging them so as to avoid any rigid connection between their main body portions where they enter the smokebox.

In the drawings which illustrate the invention—

Figure 1 is, in part, a top view and, in part, a horizontal section on the line 1—1 of Figure 2 showing a locomotive boiler support and cylinder casting embodying one form of the invention.

Figure 2 is a partial front view and partial

vertical section taken on the line 2—2 of Figure 1.

Figure 3 corresponds to Figure 1 but illustrates another form of the invention.

Figure 4 is a vertical transverse section and elevation taken on the line 4—4 of Figure 3.

Figure 5 is a vertical longitudinal section taken on the line 5—5 of Figure 4.

Figure 6 is in part a top view and in part a horizontal section illustrating another modification.

Figures 7 and 8 are detail vertical sections taken on the lines 7—7 and 8—8, respectively, of Figure 6.

Figure 9 is in part a top view and in part a horizontal section illustrating another modification.

Figure 10 is a detail section illustrating another modification.

The locomotive frame or bed 1 is shown as 75 formed integrally with main steam cylinders 2, valve chambers 3, and the smoke box support 4. The weight of the bed is carried on the usual locomotive leading truck through an integral center bearing plate 5. The support 4 is box 80 shaped and includes front wall 6, side walls 7, and back wall 8, all having top flanges 12 for mounting the smokebox. The top member 9 of the locomotive bed forms a bottom wall of the support 4. Cored openings 10 and 11 in the walls 6 and 8 facilitate molding and permit 85 access to the underside of the exhaust steam passageways 14, 15, 16, and 17. These holes are closed by means of plates welded in place after the casting is completed so that the walls and bottom plate are imperforate in the finished 90 structure.

The front and rear walls 6 and 8 of the support merge with the side walls 7 and with the steam passageways 14, 15, 16, and 17 by means 95 of arcuate sections 13 of substantial radii whereby the side walls may have some lateral movement, under the influence of expansion in the passageways, without unduly stressing the front and rear walls of the support and without tending to crack the connection between the side walls and transverse walls.

The exhaust steam passageways are integral with the side walls 7 and extend substantially horizontally inwardly from the valve chambers 3 through the support side walls 7 and then curve upwardly and project into the smokebox. The two passageways leading from the ends of one valve chamber merge with each other near their intersection with the side wall 7, but each 100 105 110

merged passageway 30 continues throughout its length independently of the corresponding passageway from the other chamber. Their terminals are substantially above the top of the central portion of the support and an inverted V shaped exhaust pipe member 22 rests on the ends of the passageways and is secured thereto by means of bolts through holes or slots in the corresponding flanges 21 and 23 and 20 and 24. An ordinary nozzle 25 rests on the top of the member 22 and is secured thereto by means of similar bolted flanges 26 and 27. Nozzle 25 discharges to the smoke stack (not shown) in the usual manner. The interengaging ends of passageways 30 and member 22 are provided with ball joints B to facilitate relative movement between them.

A liner or cover 29, for reinforcing and protecting the smokebox shell, overlies the lower portions 28 of the smokebox shell resting on the flanged tops of the upright walls of the support 4. Preferably this cover is formed of two main parts welded together along the longitudinal center line of the locomotive. The exhaust passageways extend through a hole in the cover plate 29. The inner edges of the hole in cover 29 are spaced from the outer walls of the passageways and the space between the passageways 30 is closed by a plate 33 secured to cover plate 29. On previous structures the corresponding liner was provided with an opening as large as the area between the upright walls of the support because a web was provided at the top of the support between the upright walls, which web was adapted to receive the hot ashes deposited in the smokebox.

Due to the novel construction and shaping of the support and passageways and the spaces between the passageways 30 and plates 29 and 33, all of the passageways may expand freely in any direction without unduly straining the casting. The open top of the support portion of the casting facilitates the removal of core sand and also the inspection and repair of the undersides of the exhaust passages during the process of manufacture.

In the modification shown in Figures 3, 4, and 5, the cylinder saddle including the smokebox support is in the form of a cast unit applied to the usual locomotive main frame side members 40. The cylinders 41, valve chambers 42, and exhaust steam passageways 43 are integral with each other and the inner upper ends of the passageways 43 merge with each other as indicated at 44. The smokebox support has side walls 45 and front and rear walls 46 and 47, respectively, corresponding to the saddle of Figures 1 and 2. The bottom wall 48 of the support extends from cylinder to cylinder and is provided with depending webs 49 braced from the cylinders 41 and adapted to be bolted to the main side frames 40 in the usual manner.

The merged portion 44 of the steam passageways 43 is spaced a substantial distance above the top of their outer horizontal portions and this arrangement, together with the offset connections 50 with the front and rear walls 46 and 47, permits the passageways to expand and contract relative to the smokebox support walls without setting up undue strains in the latter or in the passageways.

The top of the support is substantially closed by means of a pair of liner plates 51 overlying the inner edges of the smokebox sheets 52 and 751 welded together along the longitudinal center

of the locomotive, as shown at W, and supported on bosses 53 on the outer walls of the passageways. An opening in the liner plates receives the passageways 43 as in the form shown in Figures 1 and 2.

In the modification shown in Figures 6, 7 and 8, the steam passageways 55 leading from the rear ends of the chambers 56 enter the saddle at the rear corners thereof and merge with the side wall 57 and rear wall 58 and are joined together at 55a near their outlet portions and are curved about a horizontal radius substantially throughout their length to accommodate expansion without excessive strains in the saddle structure and without affecting the spacing of the steam chambers 56.

The exhaust passageways 78 leading from the front end of the chambers 56 have a reverse curve and terminate in outlet portions merged with the corresponding portions of passageways 55. These front passageways 78 do not merge with the side walls 57 of the saddle but extend through openings 59 provided in the side walls similar to other structures described in my copending application Serial No. 547,136.

By extending the rear passageways 55 through the corner portions of the saddle, the joint between the side and rear walls of the saddle is relieved of expansion strains. By placing the front passageways 78 through openings in the side walls of the saddle, the front corners are relieved of similar strains.

This construction is made possible by the use of a transverse beam consisting of the top wall 54 of the bed and lateral extensions 54a thereof which cooperate with vertical webs 54b to mount and support the cylinders C and supply chambers 56 independently of the boiler-supporting and exhaust-passageway-containing portion of the saddle. This structure is more specifically described and claimed in my copending application Serial No. 547,136.

In the somewhat similar modification shown in Figure 9, both of the passageways 60 and 61 on one side of the saddle extend through an elongated opening 62 provided in the corner formed by side wall 63 and front wall 64 of the saddle. The passageways 60 and 61 on one side of the saddle merge with each other before the longitudinal center line of the saddle is reached and the corresponding passageways 66 and 67 on the other side of the saddle similarly merge on the other side of the center line. All of the passageways then merge with each other in the outlet portion 65. The passageways 66 and 67 enter the saddle through an opening at the rear corner and the complete passageway structure forms a double curve leading from the supply chamber 68 on one side of the saddle to the supply chamber 69 on the other side of the saddle. This provides arcs of relatively large radius for accommodating the expansion tendencies of the heated walls of the steam passageways.

Figure 10 illustrates an inverted V-shaped exhaust pipe, one leg of which includes a lower portion 70 having a universal joint connection with the upper portion 71 which is rigid with the other leg 72. The lower ends of both legs have universal joint connections with the outlet portions 73 and 74 of the exhaust passageways. This construction provides the exhaust member with a greater degree of flexibility and thereby more readily accommodates substantial movement of the passageway outlets 73 and 74.

Each of the above described structures is a saddle casting which extends from side to side of the locomotive and includes the opposite main steam cylinders in an integral structure. It is common practice to form cylinder and smokebox saddles in two halves adapted to be bolted together either along the longitudinal center line of the locomotive or to one side thereof. The present invention may be embodied in such constructions and when utilized will tend to eliminate the stresses on the attaching bolts and thereby avoid the necessity of frequent inspection and tightening of the same.

While the invention is described as embodied in a steam locomotive, it is to be understood that many of the features may be advantageously employed in an engine utilizing motive fluid other than steam and the desirability of relieving strains in the structure may arise from contracting tendencies as well as from expansion tendencies.

Another structure directed towards the same general result and embodying some of the features illustrated herein is covered by a co-pending application of E. G. Hallquist and myself, Serial No. 541,894, filed June 3, 1931, now Patent No. 1,864,736, issued June 28, 1932.

Obviously, various other modifications as to details and different combinations of the particular features may be made without departing from the spirit of the invention and I contemplate the exclusive use of all such variations and combinations as come within the scope of my claims.

35 I claim—

1. In a locomotive, a smokebox support, and fluid passageways rigid with the sides of said support and extending therethrough and upwardly and then merging with each other, the inner portions of said passageways being free of other connections to said support within the support to relieve the structure of strains due to variations in temperature in said parts.

2. In a locomotive, a smokebox, a smokebox support having side and bottom walls forming an air excluding chamber beneath said smokebox, a plurality of fluid passageways extending through and rigid with certain of said walls, the inner portions of said passageways being free of other connections with each other and with said walls within said closure to relieve the structure of strains due to variations in temperature in said parts.

3. In a locomotive cylinder saddle, a rigid boiler support structure including a side wall, a fluid passageway rigid with and extending inwardly from said side wall and connected to said structure at its outer end only to relieve the structure of strains due to variations in temperature in said parts.

4. In a locomotive cylinder saddle, a rigid boiler support structure including side walls integral with each other, and fluid passageways rigid with and extending inwardly and upwardly from each of said side walls and connected to said structure at their lower ends only to relieve the structure of strains due to variations in temperature in said parts.

5. In a locomotive cylinder saddle, a rigid boiler support structure including side walls, and fluid passageways extending inwardly and upwardly from said side walls and separated from each other throughout their length and rigidly connected at their lower ends only to said structure side walls to relieve the structure

of strains due to variations in temperature in said parts.

6. In a locomotive structure, a smokebox, spaced side walls forming a smokebox support, fluid passageways extending inwardly from and rigidly connected to said walls, and an exhaust pipe mounted on the inner ends of said passageways, said exhaust pipe and walls being the only elements positioning the inner portions of said passageways whereby the structure is relieved of strains due to variations in temperature in said parts.

7. In a locomotive structure, a smokebox rigid support having a wall and a fluid passageway extending through and rigidly connected to said wall, the inner portion of said passageway extending inwardly and upwardly from said wall and being free of other connections to said support to relieve the structure of strains due to variations in temperature in said parts.

8. In a locomotive structure, a smokebox, walls forming a smokebox rigid support, and a plurality of fluid passageways extending through and rigidly connected to certain of said walls, the inner portions of said passageways extending inwardly from said walls and being free of other connections to said support to relieve the structure of strains due to variations in temperature in said parts.

9. In a locomotive structure, a smokebox rigid support having side walls, and a plurality of fluid passageways extending through and rigidly connected to certain of said walls, the inner portions of said passageways extending inwardly and upwardly from said walls, and being spaced from each other and free of other connections to said support to relieve the structure of strains due to variations in temperature in said parts.

10. In a locomotive structure, a smokebox support having walls, and fluid passageways extending from opposite sides through said walls and rigidly connected thereto, the inner portions of said passageways extending inwardly and upwardly and merging at a point substantially at the level of the center of the top of said support, and said inner portions being spaced and disconnected from the remaining parts of the smokebox support to relieve the structure of strains due to variations in temperature in said parts.

11. In a locomotive structure, a smokebox support member, valve chambers, and fluid passageways leading from said chambers through said member, said passageways having horizontal portions rigid with and extending inwardly from said support and having curved portions extending upwardly through said support and being spaced from each other for a substantial distance above the level of the tops of said horizontal portions to relieve the structure of strains due to variations in temperature in said parts.

12. In a locomotive cylinder saddle structure, valve chambers, upright webs forming the sides and ends of a boiler support, and fluid passageways extending from the exterior of said support at each side thereof to the interior thereof and then merging in an outlet portion whereby a continuous conduit is formed between said valve chambers, certain of said passageways being rigid with said side and end webs and other of said passageways extending through openings provided therefor in said webs.

13. In a locomotive cylinder saddle structure, valve chambers, upright webs forming the sides and ends of a boiler support, and fluid passageways extending from said chambers to the interior of said support and merging with each other in an outlet portion whereby a continuous member is formed between said chambers, certain of said passageways extending through the adjacent corners between said webs with the opposing walls of said passageways merging with the adjacent portions of said side and end webs respectively whereby a direct connection between said webs adjacent said passageways is avoided to relieve the structure of strains due to variations in temperature in said parts. 80
14. In a locomotive cylinder saddle structure, valve chambers on opposite sides of the saddle, and a continuous fluid conduit extending between said chambers in the form of a reverse curve whereby said conduit may expand or contract without forcing said chambers apart. 85
15. In a locomotive cylinder saddle structure, upright webs forming a boiler support, a beam at the end of said support projecting transversely thereof to mount cylinders and valve chambers at the ends of the latter, fluid passageways extending continuously between opposite ones of said cylinders and chambers and passing through openings in said webs and curved intermediate their ends to relieve the structure of strains due to variations in temperature in said parts. 90
16. In a locomotive cylinder saddle structure, upright webs forming front and rear walls of the boiler support, valve chambers on the sides of said support, fluid passageways extending from one of said chambers through an opening provided therefor in the adjacent rear corner of said support, and fluid passageways extending from the other of said chambers through an opening provided therefor in the adjacent front corner of said support, said passageways merging with each other at the center of said support to form a continuous member curving diagonally across said support to relieve the structure of strains due to variations in temperature in said parts. 95
17. In a locomotive boiler saddle, a base member, main steam cylinders outside of said base member, members connecting one end of each of said cylinders with said base member, steam passageways extending inwardly from both ends of each of said cylinders and merging with each other and with the passageways from the cylinder on the opposite side of the saddle, said connecting members constituting the sole connection and contact between said cylinders and said base member. 100
18. In a locomotive structure, a smokebox support having a wall and fluid passageways extending through and rigidly connected to said wall and spaced from each other throughout their length and terminating in outlets in said support, an inverted V-shaped exhaust pipe mounted on said outlets and having at least one flexible leg whereby the structure is relieved of strains due to variations in temperature in said parts. 105
